INTERLOCKING SYSTEM FOR RAILROADS

Andrew Langdon, Brighton, N. Y., assignor to
General Railway Signal Company, Rochester,
N. Y.

Application July 22, 1936, Serial No. 91,932
Renewed September 28, 1937

12 Claims. (Cl. 246—134)

This invention relates to electric interlocking systems for railroads; and more particularly pertains to an interlocking system of the entrance-exit type.

In an interlocking system of the type contemplated by the present invention, a miniature track layout is located in the central control office which corresponds to the actual track layout in the field, and on which miniature track layout are located initiating and completing buttons or levers for each end of each route. The operation of an initiating button at the entrance to a route together with the actuation of the completion button for the exit end of that route, 10 compositely controls all of the individual track switches included in that route and clears the signal for such route when all of the track switches have properly responded.

One of the objects of the present invention is to 20 provide for the control of the track switches in a manner which is particularly useful in an entrance-exit type of interlocking system as well as to provide suitable indications of the condition of such switches so as to give the operator the 25 proper information for most efficiently taking advantage of the composite type of control provided in an entrance-exit type of interlocking system.

This invention is to be considered an improvement over the entrance-exit type of interlocking 30 system disclosed in the prior application of S. N. Wight, Ser. No. 69,905, filed March 20, 1936.

Other objects, purposes and characteristics 35 features of the present invention will be in part obvious from the accompanying drawings, and in part pointed out as the description of the invention progresses.

In describing the invention in detail, reference 40 will be made to the accompanying drawings, in which like letters in the reference characters designate similar functions or relationships with the distinctiveness between such reference characters provided by the use of distinctive preceding numerals; in which like preceding numerals in the reference characters, when applied to different letters, represent the inclusion of such devices within a particular group; and in which:—

Figs. 1 and 2 when placed side by side diagrammatically illustrate the control office and field station apparatus comprising the present invention.

For the purpose of simplifying the illustration and facilitating in the explanation thereof, the conventional parts and circuits constituting the embodiment of the invention have been shown 55 diagrammatically and certain conventional illus-

trations have been employed, the drawings having been made more with the idea of making clear the purpose and principles of the present invention together with its mode of operation, than with the idea of illustrating the specific construction and arrangement of parts that would probably be employed in practice. 5

The various relays and their contacts are illustrated in a conventional manner and symbols are employed to indicate connections to the terminals of batteries or other suitable sources of electric current supply instead of showing all of the wiring connections to such terminals. 10

The symbols (+) and (—) are employed to indicate the positive and negative terminals respectively of suitable batteries or other sources of electric energy; and those terminals with which these symbols are used are presumed to have current flowing from the positive terminal designated (+) to the negative terminal designated (—). 15

The symbols employed with any one circuit are considered to designate the terminals of the same battery or other suitable source, but as many separate sources may be provided as found necessary or as many sources may be combined into a single source as found necessary or expedient in the practice of the invention. If alternating current is employed, then these symbols should be considered to represent the instantaneous relative polarities of the respective 25 terminals. 30

Where groups of devices are referred to in a general way, such devices will be designated by the letters or preceding numerals characteristic 35 of such groups instead of reciting each specific reference character of that group of devices.

Apparatus in general

Track layout.—In Fig. 2 of the accompanying 40 drawings, the invention has been shown applied to a track layout including a stretch of double track connected by a crossover having switch points TSA and TSB. The stretch of double track includes a main line extending from a signal 2 to a signal 4, and another main line extending from a signal 3 to a signal 5. Signals 2 and 5 govern the traffic over the crossover as well as over the main line tracks with which they are associated. 45

Inasmuch as the opposite ends of a crossover are usually operated at the same time, the crossover may be considered as operated by a single switch machine SM, which may be of any suitable type, such for example, as disclosed in the patent 50 55

to W. K. Howe, Patent No. 1,466,903, dated September 4, 1923. However, two switch machines may be employed all within the scope of the present invention.

- 5 It should also be understood that the invention is not limited, as thus shown, to the control of a crossover and signals of this chosen layout, but may be extended for any desired number of switches and signals and may be readily applied 10 to all types of track layouts found in interlocking plants. The manner in which the present invention applies to a single track switch instead of a crossover, will be pointed out hereinafter by describing those parts of the present disclosure 15 which may be readily omitted when only a single turnout switch is controlled by a system constructed in accordance with the present invention.
- The signals 2, 3, 4 and 5 are assumed to be 20 color light signals giving the usual indications of green for clear and red for danger or stop, and yellow if an added indication is desired for caution. However, these signals may be of the 25 searchlight type, the semaphore type, or any other suitable type instead of the type chosen for the embodiment of the present invention.

The track layout has been shown as divided 30 into two track circuits 6 and 7 by insulated joints, which track circuits are provided with the usual track batteries and track relays of which track 35 relays 6T and 7T have been shown. These normally energized track circuits are wired in the usual manner to provide for fouling protection and to provide for the insulation of the track switches, such details of wiring having been omitted for the sake of simplicity in the disclosure.

- The crossover including track switches TSA and TSB is shown as having a single switch 40 repeating relay WP of the polar neutral type. This relay WP is energized with one polarity or the other in accordance with the normal and reverse locked positions of the track switches TSA and TSB and the switch machine SM in corresponding positions, and is deenergized 45 whenever the track switches are unlocked or are in operation. The polarized circuit for controlling such a switch repeating relay may be governed by any suitable means, such as ordinary switch boxes, but is preferably governed through 50 the medium of a point detector contact mechanism such as shown for example in the patent to C. S. Bushnell, Patent No. 1,517,236, filed November 25, 1924, it being understood that there would of course be two such mechanisms when 55 two switch machines, such as switch machine SM, are employed.

Control panel.—A control machine in the central office is provided with a control panel on which is located a track diagram corresponding 60 to the actual track layout in the field. The crossover in the field is represented by a miniature crossover *ts* which is movable to normal or reverse positions by electro-magnetic means including normal and reverse operating coils N 65 and R of the magnetic operator MO. The control panel also includes an entrance button NB for each of the signal locations, such as entrance buttons 2NB, 3NB, 4NB and 5NB for the respective signals 2, 3, 4 and 5. An exit button XB is 70 also provided for the end of each route, shown specifically as exit buttons 2XB, 3XB, 4XB and 5XB. It is to be understood, that the ends of the route may or may not correspond to the location of the exit buttons on the miniature track diagram, as a route is usually considered to extend 75

from one particular signal to the next signal governing traffic in the same direction or to some arbitrarily chosen point.

Each entrance button NB is in the form of a knob which is rotatable from a normal position to an operated position. The operation of this knob 90° in a clockwise direction operates suitable contacts to close a circuit which energizes its corresponding entrance relay. This has been merely indicated by a dotted line, as the details have been shown in the above mentioned prior application of S. N. Wight, Ser. No. 69,905, filed March 20, 1936.

Within each entrance button NB is a suitable signal indicator SK which is illuminated whenever and only when its corresponding signal is indicating clear. Thus, the indicators 2SK, 3SK, 4SK and 5SK indicate the cleared condition of their respective signals 2, 3, 4 and 5, all of which is accomplished through means not shown in the present disclosure for the sake of simplicity, although reference may be made to the above mentioned application, Ser. No. 69,905, for the details of such control.

The exit buttons XB are of the self-restoring push button type which have been shown as connected to the contacts which they operated by a dotted line so as to make the relationships more readily apparent.

The track diagram also includes track indicators 6TK and 7TK which are illuminated whenever the corresponding track sections are occupied by a train as indicated by the track sections are occupied by a train as indicated by the track relays 6T and 7T respectively. The control for these indicators is assumed to be of any suitable type and has been omitted from the disclosure for the sake of simplicity.

Beneath the movable points of the miniature crossover *ts*, are lock lamps LKA and LKB corresponding to the respective switch points TSA and TSB, which lock lamps are illuminated whenever the crossover TS is locked against operation, or is being controlled to a new position, all of which will be described in detail herein- 45 after.

An emergency switch control lever SML is also provided to control the operation of the switch machine SM under certain emergency conditions hereinafter pointed out in detail. This lever may 50 be suitably located upon the control panel, or may be located on the back of the control machine, as desired, because of the fact that such lever is only used for emergency conditions. This control lever SML has associated therewith 55 an indicator lamp COR which is illuminated whenever the crossover TS is in midstroke position or is out of correspondence with its switch machine control as set up by the composite route control or by the emergency lever SML.

Route relays.—The control office equipment also includes a route relay for each of the routes. These route relays are selectively controlled by the entrance and exit buttons NB and XB, as pointed out more in detail hereinafter, and include relays 3—5, 2—5 and 2—4 for controlling traffic between the signals represented by the numbers in such route relay reference characters.

The route relays provide for the positioning 70 of suitable switch control relays WNA, WR and WNB, which relays control the operation of the switch machine SM. Associated with this control for the switch machine is a lock relay L which prevents the operation of the switch machine 75

when it is unsafe for the track switches TSA and TSB to be operated.

Relays NCR and RCR are provided to indicate when the track switches are in correspondence with their control as will be pointed out herein-after.

The route relays 3-5, 2-5 and 2-4 also control the clearing of the signals through suitable circuit selections which control the signal relays 2G, 3G, 4G and 5G for the respective signals indicated by the preceding numerals.

In an interlocking system, there is usually suitable approach locking and route locking associated with the signal and switch controls and this disclosure considers the application of any suitable route locking to the system of the present invention, but for the purpose of illustration, directional stick relays 6ES, 6WS, 1ES and 1WS are associated with the track circuits 6 and 7 respectively, to provide what is termed rear release route locking all of which has been disclosed in the prior application of Larry et al. Ser. No. 577,504, filed November 27, 1931, to which reference may be made for the details of the control for such relays.

It is considered sufficient for an understanding of the present invention to know that the relay 6ES, for example, is deenergized when the signal 2 is cleared and is maintained deenergized although the signal is returned to stop so long as a train is on the track circuit 6, but during such deenergized condition of the relay 6ES, the relay 6WS remains picked up. Similarly, the relay 6WS is deenergized when the signal 4 is cleared and remains deenergized so long as a train is on the track circuit 6 although the signal 4 is restored to stop, but during such deenergized condition of relay 6WS, the relay 6ES remains picked up.

Likewise, the relay 1ES is deenergized whenever the signal 3 is cleared and is maintained deenergized although the signal is returned to stop so long as a train is on the track circuit 1, but during such deenergized condition of the relay 1ES, the relay 1WS remains picked up. Similarly, the relay 1WS is deenergized when the signal 5 is cleared and remains deenergized so long as a train is on the track circuit 7, although the signal 5 is restored to stop, but during such deenergized condition of the relay 1WS, the relay 1ES remains picked up.

It is also noted in this connection that when the track switches TSA and TSB are in reverse positions to allow traffic to pass over the crossover, and the signal 2 is cleared both the relays 6ES and 1ES are deenergized; and similarly, when the signal 5 is cleared for traffic in an opposite direction over the crossover both the relays 6WS and 1WS are deenergized.

It is believed that the remaining features of the present invention will be best understood by considering the detailed operation of the system.

Normal conditions. — Although the track switches TSA and TSB are usually left in their last operated positions, they have been shown in positions for the passage of main line traffic. The signals are of course normally "at stop" with the lower or red indicator of each signal normally illuminated, unless approach lighting features are employed in accordance with the usual practices.

With the track sections 6 and 7 unoccupied, the track relays 6T and 7T are of course normally picked up.

The lock relay L, the directional stick relays

6ES, 6WS, 1ES and 1WS, and the particular correspondence relay NCR or RCR for the position of the track switches TSA and TSB are normally energized, but these circuits will be pointed out in detail in connection with the description of their operation.

All the route relays in the central office and the indicators on the control panel are normally deenergized to provide what has been conveniently termed a "normally dark board".

Entrance-exit route interlock. — When the operator desires to set up a route from the signal 2 to the signal 4, for example, he rotates the entrance button 2NB 90° in a clockwise direction which closes suitable contacts to energize its repeating relay 2NR, in which position the entrance button 2NB remains until manually restored to put the route which it governs to stop, as later described. After actuating the entrance button 2NB, the operator then glances along the miniature trackway and finds that there are no lock lamps LK illuminated between such entrance button 2NB and the exit button 4XB which designates the end of the route which he desired to set up. If a lock lamp, such as lock lamp LKA, is illuminated with the miniature crossover ts in a position opposite to the position required for the desired route, then the operator is advised that he cannot set up the new route. However, assuming that the lock lamp LKA is not illuminated and that the miniature crossover ts is in a normal position (or it might be in a reverse position), the operator actuates the exit button 4XB.

The contemporaneous operation of the entrance button 2NB and the exit button 4XB closes a pick-up circuit for the route relay 2-4 from (+), through a circuit including front contact 10 of relay 2NR, back contact 11 of route relay 2-5, windings of route relay 2-4, back contact 12 of relay 4NR, back contact 13 of exit button 4XB, to (-). The current which flows in this circuit causes the polar contacts of the route relay 2-4 to be operated to right-hand positions and the neutral contacts to be picked up.

As soon as the contacts of the route relay 2-4 respond, a stick circuit is closed from (+), through a circuit including front contact 10 of relay 2NR, back contact 11 of route relay 2-5, windings of route relay 2-4, polar contact 14 of route relay 2-4 in a right-hand position, front contact 15 of route relay 2-4, to (-).

Each of the remaining route relays 3-5 and 2-5 are picked up in a similar manner and are maintained energized dependent upon stick circuits which are wholly dependent upon the return of their respective entrance buttons NB to normal at stop positions. Such control for these remaining route relays will be readily apparent from the drawings and will not be described in detail.

The picking up of the route relay 2-4 opens its back contact 16 which prevents the picking up of the route relay 2-5 for establishing a conflicting route over the crossover. Similarly, the pick-up circuit for the route relay 2-5 also includes back contact 17 of route relay 3-5 so that the route relay 2-5 cannot be picked up whenever there are parallel routes established by either or both of the route relays 3-5 and 2-4.

It is also apparent that the pick-up circuit for the route relay 2-4 includes back contact 11 of route relay 2-5 so that if such route relay 2-5 were picked up for the establishing of a route over the crossover, that the route relay 2-4 could not

be picked up. A similar interlock is provided between the route relays 3-5 and 2-5 by the back contact 18 of the route relay 2-5.

In brief, it will be apparent that any number of route relays for parallel or non-conflicting routes may be picked up at the same time, while only one route relay from among a plurality of route relays for conflicting routes may be picked up at any one time.

10. *Switch control.*—For each crossover, a switch control relay WNA is provided for one end of the crossover in a normal position and a relay WNB for the opposite end of the crossover in a normal position, while a switch control relay WR is provided for both ends of the crossover in reverse positions.

The route from the signal 2 to the signal 4 requires the track switch TSA to be in a normal position so that the picking up of the route relay 2-4 provides for energizing the switch control relay WNA by a circuit closed from (+), through a circuit including front contact 19 of route relay 2-4, bus wire 20, windings of relay WNA, back contact 21 of relay WR, to (-).

25. The picking up of the relay WNA closes the normal operating circuit for the switch machine SM from (+), through a circuit including front contact 22 of track relay 7T, front contact 23 of track relay 6T, front contact 24 of lock relay L, front contact 25 of relay WNA, through the switch machine SM, to (-).

If the route relay 2-5 were picked up, which requires the track switches TSA and TSB to be in reverse positions, a circuit would be closed for 35 energizing the relay WR from (+), through a circuit including front contact 26 of relay 2-5, bus wire 27, back contact 28 of relay WNA, windings of relay WR, back contact 29 of relay WNB, to (-).

40. The picking up of the relay WR would close the reverse operating circuit for the switch machine SM from (+), through a circuit including front contact 22 of relay 7T, front contact 23 of relay 6T, front contact 24 of relay L, back contact 25 of relay WNA, front contact 30 of relay WR, through the switch machine SM, to (-).

On the other hand, if the route relay 3-5 were picked up, which requires the track switch TSB to be in a normal position to establish a route 50 from the signal 3 to the signal 5, a circuit would be closed for energizing the switch control relay WNB, from (+), through a circuit including front contact 31 of relay 3-5, bus wire 32, back contact 33 of relay WR, windings of relay WNB, to (-).

The picking up of relay WNB would apply energy to another normal operating circuit for the switch machine SM, closed from (+), through a circuit including front contact 22 of track relay 60 7T, front contact 23 of track relay 6T, front contact 24 of relay L, back contact 25 of relay WNA, back contact 30 of relay WR, front contact 34 of relay WNB, through the switch machine SM, to (-).

65. From this description it will be understood that either or both of the switch control relays WNA and WNB may be energized at any one time, so that, when the relay WNA is energized at the same time with the relay WNB, or alone, the switch machine SM is controlled to a normal position through the contact 25, but when the relay WNB is energized alone the switch machine SM is controlled to a normal position through the contact 34. But neither of these relays WNA or WNB 75 can be energized when the relay WR is picked up

because of contacts 21 and 33. Also, the picking up of the relay WR causes the operation of the switch machine SM to a reverse position through front contact 30, which relay WR can be picked up only when both the relays WNA and WNB are deenergized by reason of contacts 28 and 29.

The bus wires 20, 27 and 32 are not only controlled by the route relays shown, but are also selectively energized by any other route relays which may govern traffic over the track switches 10 TSA and TSB.

Returning now to consider the operation when the route relay 2-4 is picked up and energizes the relay WNA, the closure of front contact 35 of relay WNA energizes the lock lamp LKA over 15 wire 36, while the closure of front contact 37 completes a circuit for the magnetic operator MO from (+), through a circuit including back contact 38 of relay WNB, front contact 37 of relay WNA, wire 39, to the normal operating coil N of 20 the magnetic operator MO, to (-). This energization of the normal winding N of the magnetic operator MO causes the miniature crossover 25 to be operated to a normal position, if it is not already in such position.

When the crossover, including track switches TSA and TSB is in a normal position, then the contacts of the relay WP are in positions as shown so that upon the picking up of the relay WNA, the lock relay which is normally energized, is 30 immediately deenergized.

More specifically, the lock relay L is normally energized by a circuit closed from (+), through a circuit including front contact 40 of relay 6T, front contact 41 of relay 7T, back contact 42 of 35 relay 5G, back contact 43 of relay 3G, back contact 44 of relay 4G, back contact 45 of relay 2G, back contact 46 of relay WNB, back contact 47 of relay WR, back contact 48 of relay WNA, windings of relay L, to (-). Thus, it is readily apparent that the energization of the relay WNA opening back contact 48 causes the relay L to drop away with relay WP indicating the normal condition of the crossover.

On the other hand, if the crossover is indicated by the relay WP as being in a reverse position upon the picking up of the relay WNA, a stick circuit is closed for the relay L from the back point of contact 47 through front contact 48 of relay WNA, polar contact 49 of relay WP in a reverse position, front contact 50 of relay L, windings of relay L, to (-). The relay WNA then causes the normal operation of the switch machine SM which unlocks the track switches 55 TSA and TSB deenergizing the relay WP, which closes back contact 51 to shunt the polar contact 49 in both of its positions so upon the track switches TSA and TSB assuming normal positions, the polar contact 49 responds first to the energization of the relay WP so that the stick circuit for the relay L is maintained through front contact 48, back contact 51, polar contact 49 in a right-hand position, and front contact 50 of relay L, until the neutral contacts of the relay 60 WP pick up, at which time the stick circuit for the relay L is opened and the lock relay drops away.

The dropping of the lock relay opens contact 24 which prevents further operation of the switch 70 machine SM.

The normal correspondence relay NCR is energized by a circuit closed from (+), through a circuit including back contact 52 of the relay WR, polar contact 53 of relay WP in a right- 75

hand position, front contact 54 of relay WP, windings of relay NCR, to (-).

5 *Signal control.*—Upon the completed response of the track switches TSA and TSB and the locking of such track switches by the dropping of the lock relay L, a signal clearing circuit is closed from (+), through a circuit including back contact 55 of relay L, front contact 56 of relay NCR, wire 57, front contact 58 of route relay 2-4, polar contact 59 of route relay 2-4 in a right-hand position, wire 60, windings of relay 2G, to (-). The picking up of the relay 2G causes the change of the indication of the signal 2 from stop to clear in the usual manner.

10 15 It is to be understood that the signal 2 may have automatic control, and may also be made a stick signal, or have other features of signaling employed therewith, although such features have been omitted from the present disclosure 20 for the sake of simplicity.

25 The clearing of the signal 2 is indicated to the operator by the illumination of the signal indicator 2SK through means not shown in the drawings.

30 35 It is readily apparent that if the operator restores the entrance button 2NB to its normal position, that the route relay 2-4 will be deenergized opening front contact 58 thereby restoring the signal 2 to stop immediately upon such operation. However, the route cannot be changed until a predetermined time thereafter providing that a train is in approach to the signal 2, as contemplated in accordance with the usual approach locking practices although this has not been shown.

40 45 *Passage of a train.*—Assuming that the signal 2 is cleared and that a train passes over the route thus established, the deenergization of the track relay 6T causes the track indicator 6TK on the miniature track diagram to be illuminated advising the operator of the passage of the train onto the route. The deenergization of the track relay 6T opens front contact 23 which removes energy from the switch machine SM, in addition to the removal of energy at open front contact 24 of the lock relay L. The lock relay L is also maintained deenergized by the further opening of its circuit at contact 40 of relay 6T. Thus, so long as a train is on the track section 6, the switch machine SM is positively prevented from operation.

50 55 The entrance of the train onto the track section 6 may automatically put the signals to stop through means not shown in the present disclosure, but the operation under such circumstances is similar to the operation upon the return of the entrance button 2NB to its normal position while the route is still occupied. Assuming that entrance button 2NB has been returned, the route relay 2-4 and the signal relay 2G drop away putting the signal 2 at stop; but the relay L does not pick up because of open contact 40. The track relay 6T maintains the lock indicator LKA illuminated by energizing the bus wire 36 through back contact 61. Thus, so long as the train is on the track section 6 and the track switch TSA is locked against operation, such condition is indicated to the operator by the illumination of the route lock indicator LKA.

60 65 70 In those track layouts that have a plurality of track sections between the entering point of the route and the exit of such route, each such track section has its directional stick relays, such as relays 6ES and 6WS, associated therewith, to lock 75 the switches in the route as set forth in the

above-mentioned prior application Ser. No. 577,504. Although the entrance button 2NB is returned to stop and the train is on but the first track section in such route, the lock lamps such as LKA for all of the track switches in the route are maintained energized by reason of the fact that their respective directional stick relays for the proper direction, such as relay 6ES, are all de-energized energizing their respective lock lamps in a similar manner as closure of back contact 62 of relay 6ES energizes the lock lamp LKA. When the train passes through such track layout, releasing the route locking in the rear of the train by the picking up of the track relays for the track sections in the rear of the train and also picking up the corresponding directional stick relays, then the switches in the rear of the train are released for use in new routes and their lock lamps are unilluminated.

75 80 Thus, the inclusion of the diagrammatic and fragmentary showing of the directional stick relays 6ES, 6WS, 7ES and 7WS is to show that the illumination of the lock lamps, such as lock lamp LKA, are dependent not only upon the occupied condition of their associated track sections but also upon the route locking conditions. The track layout shown in Fig. 2 does not require rear release route locking, as diagrammatically indicated, and the back contacts of the track relays 6T are sufficient for the control of the route lock lamps in addition to the control by relays WNA, WR and WNB, but it is to be understood that the principles of the system of the present invention may be applied to any type of track layout, and for this reason the directional stick relay control has been shown.

85 90 95 *Electric lock equivalent.*—Let us assume that a train has passed onto the track section in response to a cleared route and the deenergization of relay 6T maintains the crossover locked against operation, but the operator has restored the entrance button 2NB, which cleared such route, to its normal position and inadvisably operates the entrance button 5NB in a counterclockwise direction 90° to an operated position, and then actuates the exit button 2XB in spite of the fact that the lock indicator LKA is illuminated. The relay 5NR repeats the button 5NB, as previously discussed. The route relay 2-5 is energized by a circuit closed from (+), through a circuit including front contact 63 of relay 5NR, back contact 16 of relay 2-4, windings of relay 2-5, back contact 17 of relay 3-5, back contact 64 of relay 2NR, back contact 65 of exit button 2XB. As soon as the route relay 2-5 picks up, its stick circuit is closed from (+), through a circuit including front contact 63 of relay 5NR, back contact 16 of relay 2-4, windings of relay 2-5, back contact 17 of relay 3-5, polar contact 66 of relay 2-5 in a left-hand position, front contact 67 of relay 2-5, to (-).

100 105 110 The picking up of the route relay 2-5 closes front contact 26 energizing the relay WR, but the closure of front contact 30 cannot energize the switch machine to cause its reverse operation because the front contact 24 of the lock relay L is opened and also because the front contact 23 of the track relay 6T is opened.

115 120 Let us assume that the operator maintains the route relay 2-5 in its operated position, as just described, by allowing the entrance button 5NB to remain in an operated position, then upon the departure of the train from the track section 6, the relay 6T picks up closing front contact 23 for in part preparing the circuit for the switch

machine SM. However, the lock relay L does not pick up upon the closure of front contact 40 of the relay 6T because the pick-up circuit for the relay L includes back contact 47 which at this time is open because of the energized condition of the relay WR.

In other words, if an operator endeavors to set up a route which is in conflict with an occupied route to thereby precondition a new route, such new route will not be automatically set up when the first route becomes unoccupied. In order for the second route to be set up, the operator must restore the entrance button 5NB to its normal position deenergizing the route relay 2-5 and the switch control relay WR so as to close the pick-up circuit for the lock relay L. As soon as the lock relay L has picked up, then the operator may again actuate the entrance button 5NB and the exit button 2XB causing the picking up of the route relay 2-5 and the energization of the relay WR so that the reverse operation of the switch machine SM occurs in the usual manner followed by the clearing of the signal 5.

For example, the switch machine SM operates in response to the closure of front contact 30 and the reverse correspondence relay RCR is energized upon the completed response of the track switches TSA and TSB by the closure of a circuit from (+), through a circuit including back contact 38 of relay WNB, back contact 37 of relay WNA, polar contact 68 of relay WP in a left-hand position, front contact 69 of relay WP, windings of relay RCR, to (-).

The relay NCR is of course deenergized because of open back contact 52 of relay WR and open polar contact 53 which is now in a left-hand position. The lock relay L is held up by its stick circuit including front contact 47 until the neutral contact 51 of the relay WP picks up upon the operation of the switches TSA and TSB to reverse positions. The dropping of the lock relay closes the signal clearing circuit from (+), through a circuit including back contact 55 of relay L, front contact 70 of relay RCR, wire 71, front contact 72 of relay 2-5, polar contact 73 of relay 2-5 in a left-hand position, wire 74, windings of relay 5G, to (-). The energization of relay 5G causes signal 5 to change its indication from stop to clear in a manner well understood by those skilled in the art.

With the reverse switch control relay WR picked up, it is readily apparent that both of the lock lamps LKA and LKB are energized as the front contact 75 of the relay WR applies (+) to the wire 36 while the front contact 76 of relay WR applies (+) to the wire 77. Also, the closure of front contact 52 energizes the reverse winding R of the magnetic operator MO over the wire 78, which positions the miniature crossover ts in a reverse position. This route may be put to stop simply by the restoration of the entrance button 5NB to its normal position in a similar manner as described for the restoration of the signal 2.

It is thus readily seen that the electric lock equivalent is provided for a system of entrance-exit type interlocking in such a manner that the effect of the electric lock equivalent is removed simply upon the restoration of the entrance button to its normal position, which is a distinct advance over those methods of applying such features to a system of this type thus far known, as in prior systems, the rendering effective of the electric lock equivalent, would require the additional operation of the emergency switch control

lever SML in order to restore the system to a normal condition.

Emergency switch control.—The individual manual control of track switches in an interlocking plant is at times desirable under certain emergency conditions which may arise, such as the operation of a track switch back and forth when it fails to entirely complete an operating stroke by reason of ice, lumps of coal or the like. Also, it is sometimes necessary to mechanically set up a route through the plant for the passage of hand cars and the like, although it is not desired to clear a signal for such a route. This manual control is provided in accordance with the present invention so as to be possible only so long as the track switch may be actually operated, but when it is under the control of a route relay, or is locked by reason of the presence of a train, such manual control is prevented.

This manual operation of the switch machine SM is accomplished by operating the lever SML to the right or to the left from a normal central position. When lever SML is operated to the left, it energizes the bus wires 20 and 32 to energize both of the relays WNA and WNB. The closure of front contact 25 of relay WNA is then effective to cause the operation of the switch machine SM. The lever SML provides for the picking up of both of these relays so that both of the lock lamps LKA and LKB will be illuminated while such manual control is in effect. It is noted that such energization of the relays WNA and WNB could not be accomplished if the route relay 2-5 were picked up energizing the relay WR.

The operation of the lever SML to a right-hand position energizes the bus wire 27 which causes the relay WR to be picked up to cause the reverse operation of the switch machine SM by reason of the closure of front contact 30. It is noted that the relay WR could not be energized if either or both of the relays WNA and WNB were picked up in response to control by a route relay. The energization of the relay WR likewise illuminates both of the indicator lamps LKA and LKB. Relays WNA, WR and WNB also control the miniature crossover ts in the usual way under this manual control. If either or both of the track relays 6T and 7T are deenergized, it is readily apparent that this emergency manual control of WNA, WR and WNB can not operate SM.

Control for a single track switch.—In the event that the track layout of an interlocked group includes only a single track switch, such as track switch TSA operated by the switch machine SM, then the remainder of the track layout shown in Fig. 2 is modified accordingly. In other words, the signal 3 and the track section 7 are of course absent, and the track section 6 is then arranged to include all of the track on the turnout up to the signal 5.

In the control office, the miniature track diagram is accordingly modified omitting the entrance button 3NB and exit button 3XB. The route relay 3-5 is also eliminated from the control circuits and all of its contacts removed from the circuits in which they are included in accordance with the principles of circuit work. The switch control relay WNB and its associated connections are also eliminated together with the indicator which it controls. It is believed that this simple statement for the control of a single track switch is adequate to an understanding of how the present invention is employed with a single track switch, and is also adequate for a

disclosure which will furnish the basis of claims covering the present invention applied to a single track switch.

Having thus described an interlocking system 5 of the entrance-exit route type, as one specific embodiment of the present invention, it is to be understood that various modifications, adaptations, and alterations may be applied to meet the requirements of practice without in any manner departing from the spirit or scope of the invention 10 except as limited by the appended claims.

What I claim is:

1. In a centralized traffic controlling system for railroads, a track switch, a switch machine for operating said track, normal and reverse switch control relays for respectively causing the normal and reverse operation of said switch machine, a locking relay for preventing the response of said switch machine to said normal and reverse switch control relays when such locking relay is deenergized, a pick up circuit for said locking relay including back contacts of said normal and reverse switch control relays, and a stick circuit for said locking relay including a front contact of said locking relay and contacts which complete such stick circuit only while said normal and reverse switch control relays and said track switch are out of correspondence.
2. In a centralized traffic controlling system for railroads, a track switch, a switch machine for operating said track switch, a traffic relay for manifesting traffic conditions adjacent said track switch, normal and reverse switch control relays for respectively causing the normal and reverse operation of said switch machine, a locking relay for preventing the response of said switch machine to said normal and reverse switch control relays when such locking relay is deenergized, a pick up circuit for said locking relay including back contacts of said switch control relays and a front contact of said traffic relay, and a stick circuit for said locking relay including a front contact of said locking relay, contacts which complete such stick circuit only while said normal and reverse switch control relays and said track switch are out of correspondence, and a front contact of said traffic relay.
3. In a centralized traffic controlling system for railroads, two main line tracks connected by a crossover including two track switches, power driven means for operating the track switches, a normal switch control relay for the track switch in one main line for causing the normal operation of said power driven means for that track switch, another normal switch control relay for causing the normal operation of said power driven means for the track switch in the other main line, a reverse switch control relay for causing the reverse operation of said power driven means for both of the track switches, a locking relay for preventing the response of said power driven means to said switch control relays when such locking relay is deenergized, a pick up circuit for said locking relay including back contacts of all said switch control relays, and a stick circuit for said locking relay including a front contact of said locking relay and contacts which complete such stick circuit only while said switch control relays and said track switches are out of correspondence, and front contacts of both of said traffic relays, an indicator lamp controlled by multiple front contacts on said one normal switch control relay and said reverse switch control relay also in multiple with a back contact of said one traffic relay, another indicator lamp controlled by multiple front contacts on said another normal switch control relay and said reverse switch control relay also in multiple with a back contact of said another traffic relay.
4. In a centralized traffic controlling system for railroads, two main line tracks connected by a crossover including two track switches, power driven means for operating the track switches, one traffic relay for manifesting traffic conditions adjacent one of said track switches, another traffic relay for manifesting traffic conditions adjacent another of said track switches, one normal switch control relay for said one track switch for causing the normal operation of its said power driven means, another normal switch control relay for said another track switch for causing the normal operation of its said power driven means, a reverse switch control relay for causing the reverse operation of said power driven means for both the track switches, a locking relay for preventing the response of said power driven means to said switch control relays when such locking relay is deenergized, a pick up circuit for said locking relay including back contacts of all said switch control relays and front contacts of both said traffic relays, and a stick circuit for said locking relay including a front contact of said locking relay, contacts which complete such stick circuit only while said switch control relays and said track switches are out of correspondence, and front contacts of both of said traffic relays.
5. In a centralized traffic controlling system for railroads, two main line tracks connected by a crossover including two track switches, power driven means for operating the track switches, one traffic relay for manifesting traffic conditions adjacent one of said track switches, another traffic relay for manifesting traffic conditions adjacent another of said track switches, one normal switch control relay for the track switch in one main line for causing the normal operation of its said power driven means, another normal switch control relay for the track switch in the other main line for causing the normal operation of its said power driven means, a reverse switch control relay for causing the reverse operation of said power driven means for both of the track switches, a locking relay for preventing the response of said power driven means to said switch control relays when such locking relay is deenergized, a pick up circuit for said locking relay including back contacts of all said switch control relays and front contacts of both said traffic relays, a stick circuit for said locking relay including a front contact of said locking relay, contacts which complete such stick circuit only while said switch control relays and said track switches are out of correspondence, and front contacts of both of said traffic relays, an indicator lamp controlled by multiple front contacts on said one normal switch control relay and said reverse switch control relay also in multiple with a back contact of said one traffic relay, another indicator lamp controlled by multiple front contacts on said another normal switch control relay and said reverse switch control relay also in multiple with a back contact of said another traffic relay.
6. In a centralized traffic controlling system for railroads, a track switch, a switch machine for operating said track switch, switch control relay means effective when picked up to cause the normal and reverse operation of said switch machine, a locking relay for preventing the response of said switch machine to said switch control relay means when such locking relay is deenergized, a pick-up circuit for said locking relay including back contacts of said switch control relay means, and a stick circuit for said locking relay including a front contact of said locking relay and contacts which complete such stick circuit only while said switch control relay means and said track switch are out of correspondence.
7. In a centralized traffic controlling system for railroads, a track switch, a switch machine for

operating said track switch, a signal for governing traffic over said switch, a traffic condition relay for indicating conditions of traffic adjacent to said track switch, control relay means for governing the operation of said switch machine when energized, a lock relay for allowing said control relay means to govern said switch machine only when such lock relay is picked up and for allowing said signal to clear only when such lock relay is dropped away, a pick-up circuit for said lock relay including contacts closed only when said control relay means is deenergized and said traffic condition relay is picked up, a stick circuit for said lock relay including a front contact of said lock relay and a circuit portion closed by contacts only when said track switch is out of correspondence with the energized condition of said control relay means.

8. In a centralized traffic controlling system for railroads; a track switch included in a detector track section and operable to normal or reverse positions for setting up a plurality of routes thereover; a switch machine for operating said track switch; signals for governing traffic over said routes; control buttons identifying the ends of said routes; a lock relay; normally inactive route establishing means responsive to the joint operation of the control buttons for the opposite ends of any particular route over said track switch for causing the operation of said switch machine to position said track switch to set up that route, said means being effective only when said lock relay is picked up; pick-up circuit means for energizing said lock relay only when said route establishing means is inactive and said detector track section is unoccupied; stick circuit means for energizing said lock relay, when it is once picked up, dependent upon the unoccupied condition of said detector track section and dependent upon correspondence between said route establishing means and said track switch; and circuit means controlled by said route establishing means for clearing a signal governing traffic over said particular route in response to the operation of the control buttons for the opposite ends of that route only after said track switch has set up that route and has been locked; whereby said locking relay is restored to a normally energized condition when the detector track section becomes unoccupied if said route establishing means is restored to an inactive condition.

9. In a centralized traffic controlling system for railroads; a track switch included in a detector track section and operable to normal and reverse positions for setting up a plurality of routes, a switch machine for operating said track switch, signals for governing traffic over said routes, stay-where-put entrance buttons for the ends of said routes, self-restoring exit buttons for the ends of said routes, a lock relay, normally inactive route establishing means responsive to the joint operation of an entrance button for the entrance end of a route and the operation of the exit button for the exit end of that route for causing the operation of said switch machine to position said track switch to set up such route, said means being effective only when said lock relay is picked up and remaining effective dependent upon the operated position of said entrance button for such route irrespective of the self-restoration of the exit button, pick-up circuit means for energizing said lock relay only when said route establishing means is inactive and said detector track section is unoccupied, stick circuit means for energizing said lock relay when it is

once picked up dependent upon the unoccupied condition of said detector track section and dependent upon correspondence between said route establishing means and said track switch, and circuit means controlled by said route establishing means for clearing a signal at the entrance end of said particular route in response to the operation of the entrance and exit buttons for the opposite ends of that route only after said track switch has set up that route, whereby the restoration of an entrance button restores the route establishing means to an inactive condition for the route which it is then governing, which restoration is effective to restore said locking relay to an energized condition only when the detector track section is unoccupied.

10. In a centralized traffic controlling system for railroads, a track layout including two main line tracks connected by a crossover having two track switches one in each main line, power driven means for operating the track switches, a normal switch control relay for the track switch in one main line for causing the normal operation of that track switch by said power driven means, another normal switch control relay for causing the normal operation of the track switch in the other main line by said power driven means, a reverse switch control relay for causing the reverse operation for both of said track switches by said power driven means, control buttons identified by the ends of the different routes through said track layout, circuit means responsive to the operation of the control buttons for the opposite ends of a particular route through said track layout for energizing that one of said switch control relays required to set up that particular route, a lock indicator lamp associated with each track switch, a traffic contact associated with each track switch and closed when a route including that track switch is occupied, and circuit means for each lock indicator lamp controlled by front contacts of the switch control relays for the corresponding track switch in multiple with the traffic contact for that track switch, whereby each indicator is illuminated as soon as a switch control relay is energized for such switch, and remains illuminated as long as the associated track switch is included in an occupied route although its switch control relay is then deenergized.

11. In a centralized traffic controlling system for railroads, a track switch included in a detector track section, a switch machine for operating said track switch, a track relay associated with said track switch and deenergized whenever the associated track section is occupied by a train, switch control relay means effective when distinctively energized for causing said switch machine to operate to a normal or reverse position, a lock relay for preventing said switch machine from responding to said switch control relay means when such lock relay is deenergized, pick-up circuit means for initially energizing said lock relay only when said switch control relay means is deenergized and said track relay is picked up, and stick circuit means for energizing said lock relay, when only it is once picked up, if said track switch is unlocked or is out of correspondence with said switch control relay means and said track relay is picked up.

12. In a traffic controlling system for railroads, a section of railway track including a track switch, a switch machine for operating said track switch, a track relay energized whenever said track section is unoccupied and deenergized

5 whenever said track section is occupied, a signal for governing traffic over said track switch, a three-position switch machine control lever normally assuming an inactive position and capable of being actuated to normal and reverse operating positions, switch control relay means assuming distinctive normal or reverse control conditions in accordance with the normal or reverse controlling position of the switch machine control lever and assuming a deenergized inactive condition when said switch machine control lever is in an inactive position, a lock relay, circuit means for causing said switch machine to be controlled in accordance with the normal or reverse controlling condition of said switch control relay

means only when said lock relay is picked up, pick-up circuit means for said lock relay energized only when said track relay is picked up, said signal is at stop and said switch control relay means is in an inactive condition, stick circuit means for said lock relay including contacts which are opened whenever said track switch is in correspondence with said switch control relay means, said signal is cleared or said track relay is deenergized, and a signal clearing circuit for 10 said signal energizable only when said lock relay is deenergized and said switch control relay means is in a normal or reverse control condition. 5

ANDREW LANGDON. 15
